UNITED STATES PATENT OFFICE

MAX ROHRSCHNEIDER, OF HAMBURG, GERMANY, ASSIGNOR TO SVENSKA AKTIE-BOLAGET GASACCUMULATOR, OF STOCKHOLM-LIDINGO, SWEDEN

STORAGE OF ACETYLENE

No Drawing. Application filed May 19, 1928, Serial No. 279,204, and in Germany September 27, 1927.

This invention relates to the storage of acetylene dissolved in a suitable solvent in suitable containers which are packed with absorbent material, and more particularly to 5 the storage of acetone solutions of acetylene.

A large number of filling materials for containers used for storing acetylene dissolved in acetone is known. The so-called solid filling materials possess the disadvantage that they are subsequently difficult to 10 empty out of the containers, and also that they are insufficiently porous with correspondingly inadequate powers of absorbing gas, while the loose materials in small pieces 15 all exhibit to a greater or less extent different disadvantages. If such materials consist only of a powder like substance, the gas absorptive powers are too small; if granular or fibrous material such as charcoal, kapok, 20 silk waste or the like is employed, the filling is insufficiently heat resistant.

If mixture of these insufficiently heat resistant materials with kieselguhr or the like are tried, the components readily separate 25 out within the container when the acetone used as liquid absorbent is poured in and when it is shaken to and fro during transport and use.

According to the present invention the 30 most finely disintegrated leather, which is available in abundant quantities as a by-product in leather manufacture, is employed. This material provides a reliable filling for acetylene cylinders, which satisfies all requirements on account of safety and possesses 35 an ample absorptive power.

For the purpose, the leather is shredded in a suitable apparatus until it attains a soft 40 wool like condition, so that externally it resembles somewhat the dried shredded material which is used in paper manufacture.

This leather must give a neutral reaction and should contain no components soluble 45 in acetone. Any acid must be washed out with water prior to use, and components soluble in acetone extracted with acetone. If grease-free leather waste is used, and especially chrome leather waste, a preliminary treatment with acetone is not necessary. 50 This cleaning may be performed either be-

fore or after the comminution of the leather. After cleaning, the leather is carefully dried at a suitable temperature in order to drive off the water. The shredded wool-like leather material can then be used as filling 55 by packing it into the acetylene containers. Then the acetone is poured into the containers and finally acetylene gas is led in.

With the loose fragmentary fillings previously used, a careful tight packing of the 60 material in the containers was necessary in order to obtain a reliable compacting and to avoid the subsequent formation of hollow spaces, which process entailed considerable labor and expense. On the contrary the filling with finely divided leather is appreciably 65 simpler and can be carried out in much shorter time and without the use of any other auxiliary appliances.

Fire tests made concerning the use of this 70 material have shown that it satisfies the highest demands in respect of safety.

The substance consisting of comminuted or 75 wool-like shredded leather can however be used not only alone, but also with advantage mixed with a granular or powder like heat 75 resistant material e. g. pulverized and granular pumice stone or kieselguhr.

Pumice stone, in the form in which it occurs in nature, is a soft material of little mechanical strength, which is therefore not suitable as it stands for filling acetylene containers, as it would be quickly ground to a powder within them, especially in transparent, so that the material would shake down together and form hollow spaces. To avoid this difficulty, the pumice stone granules can with advantage be mixed with the most finely divided leather, in which the granules of the mineral 80 become so embedded that a protection results against the pressure acting on them. The natural adhesion existing between the pumice stone and the leather in consequence of the fine fabrils of the latter is so great that there 85 is no fear of a subsequent separating out of the two components, such as can be observed regularly, for example, in mixtures which consist of pumice stone, charcoal or the like and kieselguhr. The material consisting of 90 95 100

leather and kieselguhr also does not subsequently separate out into its components.

I claim:—

1. A method of preparing an absorbent filling material which comprises admixing leather and an inorganic heat resistant material.
2. A method of preparing an absorbent filling material which comprises reducing leather to a finely divided state and then washing the leather with an organic solvent adapted to remove the natural acids, water and other constituents soluble in the said organic solvent.
3. A method of preparing an absorbent filling material which comprises shredding leather and then washing the same with an organic solvent to remove the natural acids and other constituents soluble in the said organic solvent.
4. A method of preparing an absorbent filling material which comprises reducing leather to a finely divided state and then washing the same with acetone.
5. A method of preparing an absorbent filling material which comprises reducing leather to a finely divided state, washing the same with an organic solvent adapted to remove the natural acids, water and other constituents soluble in the said organic solvent and then adding a heat resistant material.
6. A method of preparing an absorbent material which comprises reducing leather to a finely divided state, washing the same with an organic solvent adapted to remove the natural acids, water and other constituents soluble in the said organic solvent and then adding an inorganic substance.
7. Filling material for acetylene containers comprising divided leather mixed with kieselguhr.
8. A means for holding acetylene which comprises a pressure tight container, leather in a porous condition filling said container, a liquid solvent for acetylene, substantially filling the interstices in the leather, and dissolved acetylene under pressure within said container.

In testimony whereof I affix my signature.

MAX ROHRSCHNEIDER.
